SOAP DISH

Bennie F. Benton, 202 Sunset Drive, Hot Springs, Ark.

Filed June 10, 1963, Ser. No. 75,286

Term of patent 14 years

(Cl. D4—3)

FIG. 1 is a perspective view of a soap dish showing my new design.
FIG. 2 is a top plan view thereof.
FIG. 3 is a side view thereof.
FIG. 4 is a vertical sectional view on the line 4—4, FIG. 2.
FIG. 5 is a bottom plan view thereof.

I claim:
The ornamental design for a soap dish, substantially as shown.
